COMMUTATOR

Roy F. Carty, Washington, D. C.

Application May 6, 1935, Serial No. 20,073

4 Claims. (Cl. 171—321)

The present invention relates to improvements in commutators for electrical motors or generators and its principal object is to provide a commutator of superior construction that is comparatively easy to assemble, has the greatest strength where it is needed most and can be constructed with the least waste of material and at the greatest economy.

More particularly it is proposed in the present invention to provide a novel commutator segment which is especially strong at the ends and has the greatest radial thickness at the ends.

It is further proposed to, provide a method of making the novel segment in a very simple manner and without any waste of material.

It is further proposed to provide a novel means of securing the segments to a hub structure and a novel method for assembling the segments and the hub structure into a unit.

Further and other objects of the invention will appear as the specification proceeds.

The preferred form of my invention is illustrated in the accompanying drawing in which

Fig. 1 shows an end view of my commutator, Fig. 2, an axial section taken along line 2—2 of Fig. 1,

Fig. 3, an end view of a hub section used in my commutator,

Fig. 4, an axial section through the same,

Fig. 5, a longitudinal section through an expansion ring,

Fig. 6, a plan view of the same,

Fig. 7, a plan view showing the ring in expanded form,

Fig. 8, an axial section showing the hub sections and the expansion ring in their assembled relation prior to the application of the commutator segments,

Fig. 9 is a plan view illustrating one of the blanks or bars to be formed into a segment.

Fig. 10 is a side elevation of one of the blanks, another step in the formation of the segments. Fig. 11 is an end view thereof, Fig. 12 is still another side view, showing one of the segments during its formative stage, Fig. 13 is a side elevation of one of the completed segments; and Fig. 14 is an end view thereof as shown in Fig. 13.

While I have shown only the preferred form of my invention I wish to have it understood that various changes and modifications may be made within the scope of the claims hereto attached without departing from the spirit of the invention.

In its preferred form my commutator segment is made as shown in Fig. 10, that is in the

form of a bar 2 having tangs 3 projecting centerwise from the ends thereof, the tangs being in the same plane so as to confront one another and to define a recess 4 between the same. The tangs are tapered in their confronting faces as shown at 5 so that when the segments are arranged in the conventional annular series of a commutator the recesses define an annular groove with undercut sides.

The longitudinal sides of the segment are tapered radially in conventional form as shown at 6 and are preferably roughened and one outer edge of the segment has a slight projection 7 and is split longitudinally as at 8 to receive a connecting wire (not shown).

My segment is preferably made in the manner illustrated in Fig. 9. A bar 9 of sufficient length and material to make one segment is flattened to be about twice as wide as it is thick and is bent over into hair pin form whereupon the two legs of the hair pin are firmly pressed upon one another so that the result is a bar one-half the length and twice the thickness of the original bar, substantially square in cross-section. The bar is bent again transversely near its ends as shown at 10 so as to present a middle section 11 and two projections 12.

For assembling the segments into a commutator I utilize two hub sections 22, one of which is shown in detail in Figs. 3 and 4, and an expansion ring 23 illustrated in detail in Figures 5—7. Each hub section comprises a tubular portion 24, a conical flange 25 flaring outwardly from one end thereof and a reversed conical extension 26 projecting from the end of the flange. The ring 23 is of substantial thickness, round in section and is split, preferably on a taper, so as to be expansible, and thus forcing the flanges 25 and extensions 26 outwardly.

In assembling the commutator the two hub sections are placed together in the manner shown in Figure 8, with the ends of the flanges 25 touching and the expansible ring 23 disposed between the flanges. When the hub sections are thus arranged the two extensions flare away from one another but the extreme edges are sufficiently close to allow the segments to be placed over the extensions with a tilting movement so that the flanges are accommodated in the recesses 4 of the segments. Before the segments are applied a suitable insulating layer 28 is placed over each extension 26 and then the segments are positioned in alternating succession with similarly formed layers of mica or other insulating material.

After all the segments have been applied the

ring 23 is expanded by the use of a suitable tool such as a drift taper punch and the expanding ring forces the two hub sections apart and crowds the conical extensions 26 into the undercut sides 5 of the annular groove formed by the recesses 4 of the segments, thereby firmly interlocking the segments with the hub sections. Suitable insulating rings are provided between the hub structures and the segment assembly as in the rings 10 29 and 30 and a closure 31 made of steel or fiber and introduced between the ring 30 and the hub finishes the assembly.

I claim:

1. A commutator comprising an annular series 15 of segments having tangs projecting center-wise from the ends thereof, the tangs being tapered to define an annular groove with undercuts in the sides thereof, a pair of hub rings having reversely tapered extensions projecting into the undercuts, 20 and a resilient ring tending to urge the extensions into the undercuts for effecting a firm bond between the rings and the segments.
2. A commutator comprising an annular series 25 of segments having tangs projecting center-wise from the ends thereof, the tangs being tapered to define an annular groove with undercuts in the sides thereof, a pair of hub rings having confronting tapered flanges with reversely tapered extensions projecting into the grooves, and a split 30 ring active radially on said flanges and when ex-

panded tending to urge the extensions into the undercuts.

3. A commutator comprising an annular series 5 of segments having tangs projecting center-wise from the ends thereof, the tangs being tapered to define an annular groove with undercuts and means in gripping engagement with the undercuts for holding the segments in assembled relation comprising, a pair of hub rings having confronting tapered flanges with reversely arranged extensions, and a split expanding ring active radially on said flanges and capable of urging the extensions into said undercuts when said ring is expanded.

4. A commutator comprising an annular series 15 of segments having tangs projecting center-wise from the ends thereof, the tangs being tapered to define an annular groove with undercuts and means in gripping engagement with the 20 undercuts for holding the segments in assembled relation comprising, a pair of hub rings having confronting tapered flanges with reversely arranged extensions, and a split expanding ring active radially on said flanges and capable of 25 urging the extensions into said undercuts when said ring is expanded, said expanding ring being split diagonally and capable of being expanded.
